JEWELRY

Charles H. Phillips, Richmond, Va., assignor to
Fairway Real Estate Company, Incorporated,
Richmond, Va.

Application June 2, 1936, Serial No. 83,035

4 Claims. (Cl. 63—15)

My invention relates to improvements in jewelry; and it has for its object the provision of an improved ornamental ring or bracelet or other ornament of circular design having a movable part in which the design or the precious stone or stones is set, and which may be moved to change the design presented to the eye. This I do by making the part of the article of jewelry which bears the design or ornamental setting separate from, concentric with, and rotatable upon that part of the article of jewelry which first encircles the part of the body adorned. Another object of my invention is to provide an article of jewelry adapted for display advertising purposes.

In the drawing, which forms a part of this specification: Figure I shows in elevation my invention in a simple form; Figure II is a vertical section of a part of the ring shown in Figure I; Figure III shows my invention with an anti-friction device set between the inner band and the outer band; Figure IV is a vertical section of the article shown in Figure III; Figure V shows the jewel with a modified arrangement of the anti-friction device, and Figure VI is a vertical section thereof; Figure VII shows my invention with another form of anti-friction device; and Figure VIII is a vertical section of a part of the jewel shown in Figure VII. Figure II^a is an alternate to Figure II.

In Figure I the numeral 1 indicates the inner band of the ring or bracelet or other ornament—which I refer to hereinafter as the jewel—and 2 is the outer band, rotatably mounted on the inner band 1. The outer band 2 is quite loosely fitted around the inner band 1, so that it will rotate freely. Raised edges or flanges 3, 3 on the inner band prevent sideways displacement of the outer band 2. If desired, instead of the outside flanges 3, 3, a central bead 4 may be formed on the inner band to engage loosely in a central groove 5 in the outer band. This is shown in Figure II^a. So that the two bands may be assembled, one of them, preferably the inner band, is cut so that it may be opened or collapsed. For instance, in Figures I, II, the inner band is shown cut at 7, so that it may be collapsed and then inserted within the outer band. If the inner band is of very elastic material the cut in the inner band may be secured by any of the well known snap or lock joints. With less elastic material it is more easy to open a cut made in the outer band than it is to collapse or reduce in diameter the inner band. In the outer band 2 are set precious stones 9 or ornamental designs. When the ring or bracelet is worn, the

outer band, in which are set the stones, is readily rotated by a touch of the hand, or of the dress, so that different stones or designs are presented to view. If the two bands be made of a material which has a low coefficient of friction, and the outer band be made quite a loose fit upon the inner band, then the outer band may be made to rotate two or more times around the inner band. Such a material is celluloid. When the bands are made of a stiffer material, such as a metal, which often has a larger coefficient of friction, or when a greater number of revolutions of the outer band around the inner band are required, I then use some form of anti-friction device between the two bands. These devices are useful in another way, for by the manner in which I use them I make it unnecessary to cut either the outer or the inner band.

In Figure III I show an inner band 11 and an outer band 12, in each of which is formed a ball-race, 13 and 14; and in which the balls 15 are assembled to form an anti-friction bearing between the inner and outer bands. The stones 9 are set in the outer band 12. The depressions in which the stones 9 are set are made in one of the outer faces of the outer band 12; but one of these depressions, 16, is carried through the band; and the balls 15 are inserted into the races 13 and 14 through the hole. When the balls are in place the lower end of the hole 16 is closed by a pre-fitted plug 17, in the lower face of which a continuation of the outer ball-race 14 has been cut. When correctly adjusted, the plug 17 is secured against turning. The stone set in the hole 16 hides the plug 17. If steel balls are used, a continuous ring of such balls, as in Figure III, adds considerably to the weight of the ornament. To reduce the weight I use fewer balls, spaced in pockets, as the balls 18 shown in pockets 19 in Figures V and VI. Stones, 9, are set above each ball, and at other points if desired; and the balls are admitted into the pockets 19 through the holes 20; which holes are then closed by pre-fitted plugs 21. In the form shown in Figure III, and in that shown in Figure V, no flanges are needed to prevent displacement of the outer band on the inner band, since the engaging of the balls in the races prevents such displacement. In the type of ball-bearing which is used in machines in the industries, the balls are usually spaced apart by means of floating retainers; and the balls are inserted from the side. In my jewel it is not practicable to use a retainer. And I space the balls apart, after in-

serting them through the holes prepared for the setting of the stones, by using a separate pocket for each ball, as in Figure V. In forming the pockets 19 care is taken that the depth of the pocket at each end shall not be less than the depth at any point between the two ends; for if the depth at the end is less than the depth in the roof of the pocket, the said roof of the pocket together with the ball will form an effective clutch, which will prevent any movement of the outer band on the inner band.

A convenient and light form of anti-friction setting between the inner and outer bands is shown in Figures VII and VIII. Small wheels 31 are mounted on pins 32 set through pockets 33 in the outer band 30. It is not necessary to pierce the outer face of the band 30 to insert the wheels 31. Two or three of the wheels are set in place on their pins; and the remaining wheel or wheels are dropped into their respective pockets, their pins having been first removed. The two bands 29 and 30 are now assembled; and they are so held that the free wheels will drop into place, and their pins are then inserted. The wheels 31 engage in and roll in the race 34 in the inner band 29. Precious stones 9 are set in the outer band 30; or a design may be engraved or chased upon the outer band 30.

I claim:

1. An article of jewelry, comprising an inner band, and an outer band mounted to lie loosely around the inner band, and in the same plane as the inner band, and having a short arc of contact with the inner band so that it may be whirled about the inner band. 5

2. An article of jewelry, comprising an inner band, and an outer band mounted around the inner band and in the same plane, and having 10 an arc of contact with the inner band less in length than the circumference of the inner band so that it may be whirled about the inner band, the outer surface of the outer band being ornamented. 15

3. An article of jewelry comprising an inner band, and an outer band rotatably mounted on the inner band and spaced apart from it, stones set in the outer band, and an anti-friction device set between the inner and the outer bands. 20

4. An article of jewelry comprising an inner band, and an apertured outer band rotatably mounted about the inner band, a series of stones mounted in the apertures, an anti-friction device set between the inner band and the outer band, 25 and one of the apertures passing through the outer band to admit the antifriction device to the space between the two bands.

CHARLES H. PHILLIPS.
